(57) CLAIM

The ornamental design for multifunction BBQ mesh bag, as shown and described.

DESCRIPTION

FIG. 1 is a perspective view of the multifunction BBQ mesh bag showing my new design;

FIG. 2 is another perspective view thereof, shown with the stand in extended condition;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict portions of the multifunction BBQ mesh bag that form no part of the claimed design.
